UNITED STATES PATENT OFFICE.

PHINEAS P. MAST, OF SPRINGFIELD, OHIO, ASSIGNOR TO P. P. MAST & COMPANY, OF SAME PLACE.

CULTIVATOR.

SPECIFICATION forming part of Letters Patent No. 361,307, dated April 19, 1887.

Application filed March 1, 1887. Serial No. 229,317. (No model.)

To all whom it may concern:

Be it known that I, PHINEAS P. MAST, a citizen of the United States, residing at Springfield, in the county of Clark and State of Ohio, 5 have invented certain new and useful Improvements in Cultivators, of which the following is a specification, reference being had therein to the accompanying drawings.

On the 27th of December, 1886, Letters Patent 10 were granted to me for improvements in cultivators, and numbered 354,717, in which were shown a cross-head and a beam-bracket of peculiar construction at the point where the two are fitted together.

15 This invention relates, also, to an improvement in cultivators, having special reference to the construction of the cross-head which carries the shovel-standards and to the beam or beam-bracket to which the cross-head is 20 pivotally connected.

25 My invention consists, essentially, of a cross-head having about midway thereof an opening to receive the beam or beam-bracket, and provided with enlarged surfaces above and below that opening, and of the beam or beam-bracket having enlarged upper and lower disk-like surfaces, which fit smoothly against the surfaces of the cross-head, the beam or beam-bracket and cross-head being pivotally 30 connected together.

35 In the accompanying drawings, forming a part of this specification, and on which like letters of reference indicate the same features, Figure 1 represents a side elevation of a portion 40 of a cultivator-beam or a beam-bracket, also showing the cross-head in vertical transverse section; Fig. 2, a longitudinal vertical section of the cross-head, showing the beam or beam-bracket in transverse vertical section. Fig. 3 is a top plan view of the cross-head.

45 The letter A designates the cross-head, the same consisting of a bar constructed of cast or malleable iron, preferably the latter, and having at each end beads or shoulders B, to form seats, into which the shanks of the shovel-standards are fitted, one seat being horizontal and the other vertical. In some instances these seats are both horizontal or both vertical or one horizontal and the other vertical, as in the present illustrations. About the middle this bar

is divided and an opening formed therein, the upper and lower sides of the bar forming enlarged and substantially flat surfaces, against which the corresponding surfaces of the beam or beam-bracket are fitted. The cross-head is 55 bored vertically to receive a coupling-bolt, upon which it turns back and forth, and by which it is pivotally connected with the beam or beam-bracket. This cross-head is designed to be used particularly with cultivators in 60 which an alignment-rod is used to maintain the parallelism between the cross-head and the axle of the machine. To this end a lug, C, is formed, by preference integrally with the head, to which the rod is connected. The letter D 65 refers to the cultivator-beam, or, more strictly speaking, and according to the drawings, to the bracket which is secured to the beam proper, D'. When the beam proper is made separate from the bracket, the hub-like portion, presently to 70 be mentioned, is formed on the bracket; but should the part to which the handle is secured be formed in one piece with the beam proper, then the hub is formed on the beam. The former construction is preferred. This bracket 75 consists of a sleeve, F, and a curved arm, F', the former receiving the rear end of the beam proper and the latter connecting with the handle. Where these parts join, a hub, G, is formed, and the ends of this hub are enlarged 80 to form bearing-surfaces H. The hub is centrally bored to receive the coupling-bolt, and the surfaces H are fitted snugly to the enlarged surfaces of the cross-head, whereby the two parts are fitted together in such manner that 85 the cross-head is merely capable of oscillating on the connecting-bolt, but is held against rising at one end and lowering at the other. In other words, all twisting tendency between the cross-head and the beam is overcome and the 90 parts fitted snugly and held strongly together. This prevents either shovel from rising should it meet an unusually hard patch of ground. The alignment-rod is shown at I, being broken off. 95

Having thus fully described my invention, what I claim as new, and desire to secure by Letters Patent, is—

1. The combination, with the cultivator-beam or beam-bracket having a hub provided 100

with enlarged upper and lower ends, of a cross-head having an opening therethrough to receive said hub, and enlarged at the upper and lower ends of said opening to form bearing-surfaces, to match with the enlarged ends of said hub, and a bolt to connect the parts together.

2. The combination, with a cultivator-beam or beam-bracket having a hub whose upper and lower ends are enlarged to form flat bearing-surfaces, of a cross-head having an opening therethrough to receive said hub, enlarged at the upper and lower ends of said opening and flattened at the enlarged portions, whereby the head is prevented from twisting with respect to the hub, and a bolt to pivotally connect the parts together.

3. The combination, with a cultivator-beam or beam-bracket having a hub whose upper and lower ends are enlarged to form bearing-surfaces, of a cross-head having an opening therethrough to receive the hub, enlarged at the upper and lower ends of the opening, the portions beyond the opening forming arms to which the shovel-stands may be secured, and one of them having a lug to which an alignment-rod is secured.

In testimony whereof I affix my signature in presence of two witnesses.

P. P. MAST.
